O. DIECKMANN

SAFETY DEPOSIT APPARATUS

Filed Dec. 17, 1921

Otto Dieckmann, Inventor.
By C. W. Miles, Attorney.

UNITED STATES PATENT OFFICE.

OTTO DIECKMANN, OF CINCINNATI, OHIO.

SAFETY-DEPOSIT APPARATUS.

Application filed December 17, 1921. Serial No. 523,183.

To all whom it may concern:

Be it known that I, OTTO DIECKMANN, a citizen of the United States, residing at Cincinnati, in the county of Hamilton and State of Ohio, have invented certain new and useful Improvements in Safety-Deposit Apparatus, of which the following is a specification.

My invention relates to improvements in safety-deposit apparatus for bank vaults and similar purposes. One of its objects is to prevent the accidental or intentional insertion of a safety-deposit box belonging for instance to one person into the cell or vault compartment to which another person possesses the key. Another object is to provide such apparatus adapted to be conveniently manufactured and applied to either old or new vaults. Another object is to provide simple and inexpensive apparatus for the purpose adapted to be supplied in considerable numbers or combinations, no two of which can be interchanged through error or design to place the property of one person at the disposal of another. My invention also comprises certain details of form, combination and arrangement, all of which will be fully set forth in the description of the accompanying drawings, in which:

Fig. 1, is a front elevation of a series of safety-deposit compartments or cells of a bank-vault.

Fig. 2, is a vertical section through the same taken on line 2—2 of Fig. 1.

Fig. 3, is a perspective view of a member to be inserted into one of the safety deposit cells in advance of the safety-deposit box detached.

Fig. 4, is a perspective view of one of the safety-deposit boxes and insert members detached from the safety-deposit cell.

The accompanying drawings illustrate the preferred embodiment of my invention in which 15 represent a series of safety-deposit compartments or cells located along the interior walls of a bank vault, said cells being separated one from another by means of steel vertical walls 16 and horizontal walls 17 and provided with vertical inner end walls 18, usually the main wall of the bank-vault.

Each of said cells is provided with a door 19 hinged at 20 to one side wall and provided with a lock 21 to lock the door across the front of the cell to close the cell. The

locks 21 are so arranged as to require two keys to be employed to open any one of the cell doors 19. One of said keys is retained and supplied by the individual whose goods are to be stored in the cell and the other key which may be a master key common to several locks, is retained in the possession of an officer or employee of the bank, whereby access to the interior of the box can only be had when the bank's representative is present with his key and the owner of the contents of the box is also present with his key.

Each of said cells is provided with a container or safe-deposit box 22 adapted to closely fit within the cell, to contain the goods and papers of the individual owning or renting the box and adapted to be removed together with its contents from the cell for the purpose of inspecting its contents, and later returned to and locked within the cell. These safe-deposit boxes may be constructed of light sheet metal or other fireproof material, preferably with one or more lids 24.

In order to prevent the accidental placing of one of these safe-deposit boxes in the wrong cell which is then locked before the error is discovered so as to lose trace of where the goods of one party have been erroneously inserted and locked in the cell of another individual, and to also prevent a similar result through collusion between two or more persons to gain possession of the property of another or the dishonesty of the bank representative to thereby gain possession of the property of another, I provide an insert member 26 which may be of sheet metal, and preferably with two or more edges 27 turned so that when it is inserted into one of the cells 15 and forced against the rear end wall thereof the edges 27 will act as barbs and by engaging the side or top and bottom walls of the cell will resist withdrawal of the insert member 26 from the cell. Each insert member 26 is provided with one or more studs 28 projecting therefrom toward the door of the cells. Each of the safe-deposit boxes 22 is provided with a false rear end 29 which is provided with one or more perforations so placed and arranged as to register with and receive the stud or studs 28 of one only of the insert members 26. Thus after a designated insert member has been placed in a designated cell, only one safety-deposit box can be in-

2
serted therein a sufficient distance so that its door 19 may be closed and locked. Hence the erroneous insertion of one safety-box into a cell which was not intended to receive it would be immediately detected and the error rectified before the door could be closed and locked. In a similar manner any attempt on the part of one or more dishonest persons should attract the notice of and 10 cite the suspicions of the party to be wronged before an injury had been effected, since anything necessary to be done to permit a safety-deposit box to be locked within the wrong cell would have to be carried out in 15 the presence of the party to be wronged.

The location of the studs 28 of the respective insert members 26 in different positions vertically or horizontally, and the employment of said studs in group combinations, enables a large number of combinations to be provided, that is a large number 20 of insert members and safety-deposit boxes, in which the stud or studs of one insert member will register with the perforation or 25 perforations of the false rear end of only one safety-deposit box. If desired the insert members may be held in place by means of screws 30 through holes 31.

The apparatus is simple, inexpensive and 30 requires but little space, and is adapted to guard against serious loss. It is also applicable to prevent misplacement of file-boxes in a filing cabinet or desk, where no individual doors are employed.

35 The apparatus herein shown and described is capable of considerable modification without departing from the spirit of my invention.

What I claim is:

1. A safety deposit apparatus comprising 40 a plurality of safety-deposit cells each cell being provided with a door to be closed and locked across the entrance to said cell, a plurality of insert members to be detachably inserted into the rear ends of the respective 45 cells, and a plurality of safety-deposit boxes detachably inserted into the respective cells in front of said insert members, said insert members and safety-deposit boxes being respectively provided with members to register 50 and interengage in pairs so that only one safety-deposit box will register and interengage with each insert member to permit both the insert member and safety-deposit box to enter the cell sufficiently for the cell 55 door to be closed and locked thereon.

2. A safety-deposit apparatus comprising in combination with a plurality of safety-deposit cells having doors to be closed and locked across the entrance thereof, a plurality 60 of insert members having projections, a plurality of safety-deposit boxes each having a false rear end perforated to receive and register with a projection carried by an insert member, said insert members and safety-deposit boxes being arranged in pairs 65 with registering inter-engaging projections and perforations to permit a registering pair to enter one of said cells and to have the cell door closed and locked thereon while non-registering insert members and safety-deposit boxes will project from the cell so as to prevent the cell door closing thereon.

In testimony whereof I have affixed my signature.

OTTO DIECKMANN.
